UNITED STATES PATENT OFFICE.

ELISEO ZALLOCCO, OF SEATTLE, WASHINGTON.

MOTOR-VEHICLE LAMP.

Application filed May 25, 1926. Serial No. 111,481.

The invention is a lamp for motor vehicle head lights or the like, in which the lower portion of the reflector is removed and in which a reflector shield is placed over the 5 upper portion.

The object of the invention is to provide a reflector for lamps which eliminates the upward or glare rays and concentrates the remaining rays downwardly.

10 Another object of the invention is to provide a reflector that is only placed in the upper portion of a lamp, and that only reflects rays downwardly.

15 And a still further object of the invention is to provide a lamp of a simple and economical design which presents a neat appearance and which reflects rays of light downwardly, only.

With these ends in view the invention embodies a casing which is somewhat elongated, a lense in the front of the casing, and a reflector which is curved upward from the base of a lamp that may be placed in the center of the rear of the said casing and then 25 curved downward and forward to about the center of the said casing.

Other features and advantages of the invention will appear from the following description taken in connection with the drawings, wherein:—

Figure 1 is a longitudinal section through the lamp casing and reflector.

Figure 2 is a rear view of the said lamp casing, showing a yoke in which it is adjustably supported.

In the drawings the device is shown as it would be made, wherein, numeral 1 indicates the reflector, numeral 2 the outer casing, and numeral 3 the adjusting nut.

40 The reflector 1 is a slightly distorted semi-spherical piece of material with a comparatively sharp curve at the rear and a somewhat flattened curve at the front, as shown in Figure 1. The lower edge of the rear extends downward beyond the center to the point 4, and the lower edge of the front 45 stops at the center line of the lamp casing, as shown at the point 5. At the rear of the reflector is a lamp socket 6 which may be placed on an angle as shown so that it will hold the lamp bulb in an upwardly inclined 50 position.

The lamp casing 2 is made as shown in Figure 1, with the forward part extended to 55 accommodate the forward section of the reflector. This casing is provided with a cap

7 for holding a lens 8, and it is understood that both the cap and lens may be of any suitable design and arranged in any suitable manner. At the sides of the casing 60 are pins 9 and 10 by which it is supported in hubs 11 and 12 of a yoke 13. The hub 12 is provided with teeth 14 that engage similar teeth 15 in a boss 16 at the base of the pin 10, and it will be observed that 65 these teeth may be held into engagement by the adjusting nut 3, which is threaded on the pin 10. It will be observed that this nut may readily be loosened to adjust the position of the lamp, and then tightened to hold the 70 lamp rigid. It is also understood that any other simple means may be used for adjustably holding the lamp casing.

It will be understood that other changes may be made in the construction without departing from the spirit of the invention. One of which changes may be in the exact shape or location of the reflector, another may be in the position or arrangement of the lamp in the reflector, and still another 80 may be in the use of the reflector in a casing of a different design.

The construction will be readily understood from the foregoing description. To use the device it may be arranged as shown, 85 and it will be observed that as the lower portion of the reflector is omitted all of the glare rays from the lower portion of the reflector will be eliminated and all of the reflected rays of the lamp will be reflected 90 downward. It will be observed that when this device is used as a motor vehicle headlight it will be absolutely impossible for the operator of an approaching vehicle to see any reflected rays from the lamp, while at the 95 same time practically all of the light of the lamp will be reflected upon the roadway. The lamp may also be adjusted to permit any desired amount of the light to be reflected upon the roadway. This will, therefore, provide a lamp in which all glare rays will positively be eliminated.

Having thus fully described the invention, what I claim as new and desire to secure by Letters Patent, is:—

In a lamp of the class described, a lamp casing, a lens at the front of the casing, a substantially semi-spherical reflector in the upper portion of the casing, and a lamp bulb in the rear of the said reflector, the forward edge of the said reflector being positioned at a point approximately on the horizontal

center of the lamp casing and curving backward and upward within the casing to a point approximately at the top thereof and then curving backward and downward with a somewhat sharper curve to a point slightly below the horizontal center of the casing said curvature forming a line on a vertical plane through the center of the said reflector

and the sides of the said reflector curving downward to the lower edges thereof on lines 10 connecting the forward and rear points of the said former curvature.

In testimony whereof he affixes his signature.

ELISEO ZALLOCCO.
